(57) **CLAIM**

The ornamental design for a multi-tool, as shown and described.

DESCRIPTION

FIG. 1 is a front and left-side perspective view of a design for a multi-tool in a closed position with a head of the multi-tool in one position;

FIG. 2 is a front and right-side perspective view thereof;

FIG. 3 is a rear and right-side perspective view thereof;

FIG. 4 is a rear and left-side perspective view thereof;

FIG. 5 is a front view thereof;

FIG. 6 is a rear view thereof;

FIG. 7 is a left-side view thereof;

FIG. 8 is a right-side view thereof;

FIG. 9 is a top view thereof;

FIG. 10 is a bottom view thereof;

FIG. 11 is a front and left-side perspective view of the design for the multi-tool in an open position with the head of the multi-tool in the one position;

FIG. 12 is a rear and right-side perspective view of the design for the multi-tool in the open position with the head of the multi-tool in the one position;

FIG. 13 is a front and left-side perspective view of the design for the multi-tool in the closed position with the head of the multi-tool in another position; and,

FIG. 14 is a left-side view of the design for the multi-tool in the closed position with the head of the multi-tool in the another position.

The broken lines in the drawings depict portions of the multi-tool that form no part of the claimed design.

1 Claim, 13 Drawing Sheets
